(57) **CLAIM**

The ornamental design for a vertical-shaft-type grain milling machine; as shown and described.

DESCRIPTION

FIG. 1 is a perspective view of the vertical-shaft-type grain milling machine;

FIG. 2 is a front view of the vertical-shaft-type grain milling machine;

FIG. 3 is rear view of the vertical-shaft-type grain milling machine;

FIG. 4 is a plan view of the vertical-shaft-type grain milling machine;

FIG. 5 is a bottom view of the vertical-shaft-type grain milling machine;

FIG. 6 is a right side view of the vertical-shaft-type grain milling machine; and,

FIG. 7 is a left side view of the vertical-shaft-type grain milling machine.
